MAGNETOSTRICTIVE SIGNAL TRANSLATING APPARATUS

Harry F. Olson, Princeton, N. J., and Frank A. Hester, New York, N. Y., assignors to Radio Corporation of America, a corporation of Delaware

Application December 30, 1944, Serial No. 570,700

5 Claims. (Cl. 177—386)

1

This invention relates to signal translating apparatus, and more particularly to a magnetostriction microphone especially suitable for use under water.

There are many naval activities in connection with which acoustically responsive devices, such as microphones, are useful. For example, a microphone the output of which is connected to a mine or other explosive charge may be used to detect the presence of a sound emitting target which it is desired to destroy. For this purpose, it is generally necessary to provide a microphone which is rugged in construction and which has good sensitivity.

The primary object of our present invention is to provide an improved, magnetostriction microphone which will have these characteristics, among others.

More particularly, it is an object of our present invention to provide an improved, magnetostriction microphone which can be used to detect submarine objects with great efficiency, and which will withstand considerable abuse without becoming defective.

Another object of our present invention is to provide an improved magnetostriction microphone as aforesaid which is particularly useful in connection with mines or other explosive charges.

Still another object of our present invention is to provide an improved magnetostriction microphone as set forth above which is very simple in construction and economical in cost.

In accordance with our present invention, the microphone consists of a hollow cylinder of nickel or other magnetostrictive material adapted to vibrate radially under the influence of sound waves impinging thereon. Within the cylinder, we provide a magnetic structure which consists of a laminated core extending diametrically across the cylinder and including a polarizing magnet, the core engaging the interior surface of the cylinder at diametrically opposite points lengthwise thereof. The complete magnetic circuit comprises the polarizing magnet, which may be of laminated Alnico, if desired, the core, which may be of silicon steel laminations, and the cylindrical magnetostrictive tube. The magnet supplies a polarizing flux through the cylinder. Around the core structure is a signal coil or winding which may be suitably connected to an external amplifier. The hollow cylinder is closed off at each end by suitable plates or the like which have fluid-tight relation therewith, the magnetic structure and the coil being housed entirely with-

2

in the cylinder. If desired, the microphone may be placed in a suitable baffle.

When sound waves impinge on the cylinder, the periphery thereof is alternately contracted and expanded corresponding to the condensations and rarefactions in the sound waves. This produces a corresponding alternating change of magnetic flux in the magnetic circuit and results in the induction of an electromotive force in the coil or winding.

The novel features that we consider characteristic of our invention are set forth with particularity in the appended claims. The invention itself, however, both as to its organization and method of operation, as well as additional objects and advantages thereof, will best be understood from the following description of one embodiment thereof, when read in connection with the accompanying drawing in which

20 Figure 1 is a central, longitudinal sectional view, taken on the line I—I of Figure 2, of one form of microphone constructed in accordance with our present invention,

25 Figure 2 is a transverse, sectional view thereof taken on the line II—II of Figure 1, and

Figure 3 is a circuit diagram illustrating how our improved microphone may be connected to an amplifying circuit.

Referring more particularly to the drawing, 30 wherein similar reference characters designate corresponding parts throughout, there is shown a normally open-ended cylinder 1 of nickel or other, suitable magnetostrictive material to the ends of which are secured, by brazing or the like, 35 a pair of rings 3. A pair of end plates 5 are secured to the rings 3 in fluid-tight relation thereto, thus closing off the interior of the cylinder 1 from the ambient or surrounding medium.

Within the cylinder 1 and extending diametrically thereacross is a magnetic field structure 40 comprising a plurality of oppositely disposed, substantially T-shaped laminations 7 and one or more permanent magnets 9. The laminations 7 may be formed of silicon steel, and the magnets 9, which supply a polarizing flux through the laminations 7 and the cylinder 1, may be of Alnico, and preferably also of laminated construction. The laminations 7 may be stepped, as clearly shown in Figure 2, and are tightly clamped together, the longest ones being disposed in the center and substantially in the plane of the axis of the cylinder. The laminations 7 are arranged in two oppositely disposed groups, one or more of the longest ones of each group in a radial direction through the cylinder being so arranged that

their cross arms $7a$ engage the inner surface of the cylinder 1 along the length thereof. The legs $7b$ of the T-shaped laminations extend toward each other but are spaced a distance sufficient to receive therebetween and to firmly engage the magnets 9 . Disposed around the lamination legs $7b$ is a coil form 11 of insulating material on which is wound a coil or winding 13 . If desired, the structure thus far described may be placed within a pot-like, preferably cylindrical baffle 15 which is open at the top, the magnetostrictive cylinder 1 having an external diameter which is smaller than the internal diameter of the baffle 15 and being arranged concentrically therewith to provide an annular space 17 therebetween. The output leads from the coil 13 may be brought out in the form of a cable 19 through a fluid-tight coupling 21 of any suitable construction.

When sound waves strike the vibratory cylinder 1 , it vibrates radially by alternately contracting and expanding somewhat in correspondence with the condensations and rarefactions in the sound wave. The alternating change of magnetic flux which results in the magnetic circuit induces an electromotive force in the coil 13 , the output of which may be applied to an amplifier 23 of any suitable type. A microphone constructed as above has an impedance which is highly reactive. Its impedance can be reduced to the resistive component by inserting a capacitance 25 in series with the coil 13 . The microphone of our present invention is a relatively low impedance device, having a resistance of approximately 30 ohms at 350 cycles per second. A coupling transformer 27 may therefore be used to couple the microphone to the amplifier 23 to step up to 250,000 ohms. This confines all high impedances to the vacuum tube amplifier. The transformer may be tuned where band pass response is desired.

A microphone such as described above will be found to be extremely rugged, as evidenced by the fact that it can be struck a relatively hard blow with a hammer and dented without appreciably impairing its response. In view of the low impedance of the microphone, moisture will not impair its performance. It will be found that a microphone of this type can be made very sensitive, and its low frequency response can be increased considerably by the addition of the baffle 15 .

Although we have shown and described but a single embodiment of our present invention, it will undoubtedly be apparent to those skilled in the art that many other modifications, as well as variations in the one described herein, are possible within the scope of our invention. It will also be apparent, no doubt, that our present invention can be employed as a sound transmitter or projector, instead of as a microphone or receiver, by passing signal currents through the coil 13 which, in turn, will vary the flux in the magnetic circuit and thereby cause the cylinder 1 to vibrate and radiate sonic waves. Since the present invention is susceptible of a variety of expressions and uses, we desire that this invention shall not be limited except insofar as is made necessary by the prior art and by the spirit of the appended claims.

We claim as our invention:

1. In signal translating apparatus, the combi-

nation of a hollow cylinder of magnetostrictive material adapted to vibrate radially, magnetic means within said cylinder extending diametrically thereacross and providing a magnetic path between diametrically opposite points on said cylinder, said means including a plurality of laminations and a polarizing magnet in engagement with said laminations, and a winding disposed around said means.

2. Signal translating apparatus according to claim 1 characterized in that said laminations are shorter than the radius of said cylinder and are arranged in opposed relation spaced from each other in the region of the axis of said cylinder, and characterized further in that said polarizing magnet comprises a permanent magnet disposed in the space between said laminations in engagement with the adjacent ends of said opposed laminations.

3. Signal translating apparatus according to claim 1 characterized in that said laminations comprise substantially T-shaped member (1) the cross arms of which are arranged lengthwise of said cylinder and are in engagement with said cylinder at said diametrically opposite points and (2) the legs of which extend radially across said cylinder toward each other in opposed relation from their respective cross arms, said legs terminating in spaced relation to each other in the region of the axis of said cylinder, and characterized further in that said polarizing magnet comprises a permanent magnet disposed in the space between said laminations in engagement with the adjacent ends of said opposed laminations.

4. In signal translating apparatus, the combination of a normally open-ended, hollow cylinder of magnetostrictive material adapted to vibrate radially, closure means secured to each end of said cylinder in fluid-tight relation thereto and closing off the interior of said cylinder from the ambient, magnetic means within said cylinder extending diametrically thereacross and providing a magnetic path between diametrically opposite points on said cylinder, said magnetic means including a polarizing magnet, a winding also within said cylinder disposed around said magnetic means, and a baffle surrounding said cylinder, said baffle having a longer cross sectional dimension than the external diameter of said cylinder whereby to provide a space between said cylinder and said baffle.

5. In signal translating apparatus, the combination of a normally open-ended, hollow cylinder of magnetostrictive material adapted to vibrate radially, closure means secured to each end of said cylinder in fluid-tight relation thereto and closing off the interior of said cylinder from the ambient, magnetic means within said cylinder extending diametrically thereacross and providing a magnetic path between diametrically opposite points on said cylinder, said means including a polarizing magnet, a winding also within said cylinder disposed around said magnetic means, and a cylindrical baffle around said cylinder in concentric relation thereto, said baffle having a longer internal diameter than the external diameter of said cylinder whereby to provide an annular space therebetween.
